FLUID BOILING AND CONDENSING HEAT TRANSFER SYSTEM

Frederick Burggraf, Cincinnati, Ohio, and Archie Harold Perugi, Malvern, Pa., assignors to General Electric Company, a corporation of New York

Filed Aug. 18, 1965, Ser. No. 480,645
4 Claims. (Cl. 165—105)

The present invention is directed to a fluid boiling and condensing heat transfer system and, more particularly, to such a system for use on a structure to be cooled, which system conveniently uses sealed tubular liquid metal cooling means better known as a thermosyphon.

In many applications the limiting factor to the use of extremely high temperatures is generally the material that is available. In order to use available materials it has become necessary to devise various cooling systems to cool the structure which is to be operated at the high temperatures. A typical cooling arrangement that has been found to have useful applications is the thermosyphon arrangement which is a closed or sealed tube in which a liquid or gas may be disposed. The tube may be disposed in a centrifugal field in those cases where it is associated with rotating parts. Such an all-liquid system or all-gas system may use a single fluid and may cool by convection circulation wherein fluid is heated in one end of the tube and, being warmed, rises to the other end of the tube where it is cooled and falls back to the original tube end. This sets up a convection circulation and results in a flow fluid from one end of the tube to the other. This is what is known as free convection cooling and such cooling is well-known. Another type of cooling system is a boiling and condensing system where, using the same structure, liquid may be boiled in the heated or boiler part of the tube and then the vapor rises and flows to the cold part of the tube at the other end where it is condensed on the walls in the condenser portion. The liquid then falls back to the hot boiler end of the tube where it is again re-vaporized and the cycle continues. The division between the boiler and condenser is termed the interface. Such boiling and condensing systems may use liquid metal and are well-known.

One of the difficulties of the latter system is that it does not always operate at its maximum theoretical heat transfer capacity. A parameter which limits total heat transfer performance is the net vapor flow area available for flow from the boiler at the lower end of the tube to the condenser at the other end of the tube. Additionally, the incorrect amount of theoretically proper fluid results in poor heat transfer in that the extra fluid in the liquid form may tend to settle in the lower end of the tube when too much fluid is supplied. On the other hand, if too little fluid is supplied then the liquid will be completely vaporized before the returning condensed vapor refills the liquid supply with the result that the lower end of the tube may become dry, overheat, and melt. In other words, the correct amount of fluid results in a continuous cycle wherein the returning condensed vapor is immediately boiled to recirculate so that there is no built-up liquid supply or puddle and the system is completely balanced for maximum heat transfer capacity. In order to obtain this desirable end, it is desirable to obtain nucleate boiling off the surface of the tube. Nucleate boiling may be described as a form of boiling where the liquid is maintained on the surface and the gas bubbles that form come through the surface but do not break the liquid free from the surface. Providing this phenomenon results in very high heat losses or heat transfer such that it is possible to take a large amount of heat out of the surface of the tube. The key to maintenance of nucleate boiling is to keep the liquid film relatively thin so that the

2

gas bubbles that form or evolve come through the liquid surface and break free into the vapor atmosphere and do not take the liquid film with them. As opposed to this, film boiling permits the formation of gas on the surface, and when it leaves the surface, it lifts the liquid away from the surface to leave a gas layer thereon which insulates and reduces heat transfer capacity. Further boiling cannot take place until the liquid is returned to the surface. It is desired to maintain nucleate boiling for the highest heat transfer capabilities so that a thin liquid film flowing down the wall vaporizes off the wall and back into the vapor or gas form to immediately flow to the cold end of the tube and condense on the wall. The amount of fluid supplied must be just sufficient to fill the system and provide this thin liquid film down the wall without any excess to reduce the heat transfer and without a shortage to result in burning of the system.

The main object of the invention is to provide a fluid boiling and condensing system that is substantially completely balanced with the right amount of liquid to maintain the proper thin film on the tube surface.

Another object is to provide such a system wherein the nucleate boiling is ensured along with condensing for maximum heat transfer capabilities.

A further object is to provide such a system wherein the fluid supplied is accurately predetermined in order to provide the amounts necessary for a balanced system and thus avoid lower heat transfer capacity in the event of too much fluid and burn-out in the event of too little fluid.

A further object is to provide such a system that may be applied to a rotating structure, such as a turbine bucket, and wherein the system is so balanced that it may use a canted tube with the proper amount of fluid therein.

Another object is to provide such a system which may employ differing size tubes such as may be encompassed by tapered tubes and wherein the velocity of the fluid at the interface between the vapor and the liquid does not exceed sonic velocity.

Briefly stated, the invention comprises a fluid boiling and condensing heat transfer system that may be used on a structure to be cooled. The system comprises a sealed tubular member within the structure, the member containing a fluid such as a liquid metal although the system is not limited to liquid metal. The tube is oriented to provide a boiler at one end and a condenser at the other end and is sized to have a maximum of sonic velocity at the interface between the boiler and the condenser in accordance with the heat to be transferred at a given temperature from the member to the liquid for vaporizing the liquid. For a certain temperature level at the interface and a certain maximum heat flow, the sizing of the tube is determined in accordance with a formula that provides choked flow at the interface. Further, the minimum amount of liquid provided in the system is made up of the summation of the weight of fluid in its vapor state and the weight of fluid in its liquid state as determined by specific formulae.

While the specification concludes with claims particularly pointing out and distinctly claiming the subject matter which is regarded as the invention, it is believed the invention will be better understood from the following description taken in connection with the accompanying drawings, in which:

FIGURE 1 is a diagrammatic cross-sectional view of a typical boiling and condensing heat transfer tube;

FIGURE 2 is a partial perspective view of the system as it may be applied to a turbine bucket;

FIGURE 3 is a diagrammatic showing of an area changing tube being shown in the normal tapered form; and

FIGURE 4 is a modification of an area changing tube over that of FIGURE 3 showing another form within the term "tapered."

Referring first to FIGURE 1, there is shown a general form of known boiling and condensing system with "g" forces shown by the block arrow, which may comprise a tube 10 of any cross-sectional shape supplied with a fluid 12 and which, for convenience, is described herein as a liquid metal thermosyphon as it might be applied to a turbine bucket 13 as shown in FIGURE 2 but may be applicable to any structure that is designed to be cooled at one portion and has means for taking heat away at another portion. The turbine bucket is a convenient execution and a normal application for the system. The liquid metals may preferably be used because of their high heat transfer capabilities. If the temperatures are proper, any suitable fluid may be employed.

In the normal operation of the boiling and condensing system, the fluid 12 is boiled by the addition of heat as shown by the arrows 14 and this may be due to the hot gases passing over the turbine bucket. Boiling of the fluid 12 creates a vapor which passes as shown by the heat arrows 15 from the boiler 16 to the other end of tube 18 which is a condenser. At this end of the tube, the heat is removed by any suitable means, e.g., a cooling fluid, as presented by the arrows 20. The removal of the heat, of course, condenses the fluid on the walls of tube 10 and the fluid flows down the walls to the supply 12 and the cycle is repeated. This is a common and well-known boiling-condensing liquid metal system.

It has been found desirable that the supply of fluid 12 be kept substantially exactly correct at a given temperature condition to be handled in order that the system may be completely balanced for maximum heat transfer capacity. In other words, if too much fluid is supplied at 12 then it reduces the heat transfer capacity inasmuch as the returning liquid on the walls of the tube must lie in a pool before sufficient heat is added to vaporize the fluid again. The desired condition is to have the fluid returned on the tube wall and immediately vaporize that there is never any built-up supply or puddle of fluid at 12. On the other hand, it is desired to have sufficient fluid so that it is not all boiled away from 12 before the returning fluid reaches 12 as it comes down the walls. In that situation the tube would clearly melt or burn.

The instant invention proposes a two-fold improvement on such a known system. Summarized, this consists in providing the correct flow area and the correct amount of liquid to meet these objects.

One of the parameters which limits the total heat transfer performance in such a system is the net vapor flow area available for flow from the boiler at one end of the tube to the condenser at the other end of the tube.

In the boiler portion of the tube, heat is transferred to the liquid flowing along the tube walls towards the boiler end. This heat causes the liquid to vaporize and generate a vapor which is forced towards the condenser end of the tube by vaporization of successive quantities of liquid passing along the walls of the boiler section. As the vapor flows from the boiler to the condenser portion, its flow rate is increased by additional vapor which is generated along the length of the boiler portion walls. The flow rate of the vapor continues to increase until no additional vapor is added to the vapor flow. This point is generally found at the interface 22 between the boiler and the condenser. The interface 22 may be the physical separation point between the boiler portion and the condenser portion of the heat exchanger or the point at which no heat is being transferred to or from the fluid. By increasing the amount of heat transferred to the fluid in the boiler section, the maximum flow rate of the vapor is increased. However, the flow rate of the vapor is limited to a condition wherein the velocity of the vapor at the interface is sonic or choked.

The maximum heat transferred during this condition is

$$H = \rho_{\text{sat}} A_t C L$$

wherein:

5 H =the heat transferred from the boiler portion in B.t.u.'s/hour

ρ_{sat} =the density in pounds/cubic foot of the vapor at saturation

10 A_t =the cross-sectional area in feet squared of the tube at the interface between the boiler and the condenser portions

L =the latent heat of vaporization in B.t.u.'s/pound of the fluid circulating between the boiler and condenser portions

15 C =the sonic velocity in feet per hour of the vapor at saturation

Therefore, with the above formula, it is possible to determine the minimum cross-sectional area of a tube to enable transfer of a given maximum heat capacity. The above formula enables selection of a minimum cross-sectional area for use in meeting the maximum anticipated heat transfer requirements.

20 Thus, at a given temperature, for example 1400° F., if it is desired with a normal straight tube as shown in FIGURE 1 to cool or prevent the temperature from exceeding 1400° F. then it may be calculated how many B.t.u.'s must be removed and the required area A_t of the tube may be determined from the above formula.

25 This minimum area requirement becomes increasingly important when the tube is incorporated in a turbine bucket of a gas turbine engine. In this case, it is important that the cross-sectional area of the cooling tube be at a minimum because of the relatively thin width of the blade. In order to further minimize the area taken up by the tube, the walls of the tube are tapered from the interface to the boiler and condenser portion respectively.

30 It will be apparent that a tapered tube, such as shown in FIGURE 3, can better accommodate these vapor flows than can a straight walled tube. In this sense, the term "tapered" as used herein is intended to include a varying area sized tube such as shown in FIGURE 3 or the modified stepped portion as shown in FIGURE 4 or equivalents wherein the area is varied for the purpose herein. Any means that provides a variable area within the tube is intended to fall within this term "tapered" since it will be apparent that FIGURE 4 represents a series of holes with progressively increasing size to the center of the tube. By this tapering arrangement, boiler vapor flows can be accommodated while maintaining suitable diameters in individual regions.

35 The result of the orientation of the tube with the boiler at one end and the condenser at the other end as explained in the sizing according to the above formula, is that a tube is provided with a minimum area and a maximum heat transfer capacity at a given temperature. Additionally, it is important that the velocity at no place over the tube length exceeds sonic. This may be obtained by sizing the tube and tapering from the interface according to the above formula so the taper produces a maximum of sonic velocity at the interface and the result, in part, provides for nucleate boiling and assists in obtaining maximum heat transfer.

40 An additional important feature is the amount of liquid fill and its effect on the tube performance. There is a minimum fill level which will permit operation at maximum heat transfer capacity. With increased heat input beyond this minimum the tube is subjected to a condition where all of the liquid metal fill enters into the circulating boiling-condensing flow process and a small amount of additional heat would result in no liquid available for vaporization and thus absorption of heat. Under this condition as previously noted, the end of the boiler will be dry and temperatures will rise rapidly resulting in tube melting. In other words, there is a cor-

rect minimum fill required for the complete balance for maximum heat transfer. Within the tolerance of this amount, which is a minimum, a slight additional amount of fluid may be added to take care of manufacturing tolerances.

The minimum fill of fluid, that is needed to fill the vapor and liquid flow system for operation under the conditions described, is the sum of the weight of fluid in the vapor state plus the weight of fluid in the liquid state. The weight of fluid in the vapor state in pounds in the system can be obtained by summing up the density-volume products over the entire tube length according to the formula:

Fluid vapor weight in pounds (g) =

$$\int_{\text{condenser base}}^{\text{boiler tip}} \rho_v A_t dx$$

where;

ρ_v = vapor density, pounds/ft.³

A_t = tube cross-sectional area in ft.² at a given distance x

x = incremental length (dx) in feet

The above must be made as a summation since there is a calculable temperature variation over the system length so that the vapor density will vary from the condenser base to the boiler tip.

The weight of the fluid in the liquid state is determined by the heat flux to be transferred at the particular design tube operating condition which will dictate maximum thickness at the boiler-condenser interface plane. Thickness above and below this plane is dictated by heat flux distribution as received by the boiler and as dissipated by the condenser. The normal fluid flow equations for a falling film with friction at the wall can be used to determine fluid velocity along the surfaces. Thus, the weight of the fluid in the liquid state in pounds is determined as follows:

Fluid liquid weight in pounds (g') =

$$\int_{\text{condenser base}}^{\text{boiler tip}} \rho_L P \delta dx \quad 40$$

where;

ρ_L = liquid density, pounds/ft.³

P = tube perimeter in feet

δ = film thickness in feet

x = incremental length (dx) in feet

Both of the above fluid vapor weight and fluid liquid weight are integrated between the same limits, i.e., the condenser base and the boiler tip.

The sum of these two weights of fluid in the vapor state and fluid in the liquid state will then be the minimum fluid required for proper balanced operation of the boiling and condensing system for maximum heat transfer. This is illustrated in FIGURE 5 which shows the fluid fill level for a tube with a constant diameter. For tubes with tapering diameter, the curves would be expressed in terms of fluid fill level as a percentage of tube length versus the tube volume.

The maximum fill level (also shown in FIGURE 5) is dictated by the heat flux distribution near the tip of the boiler. Obviously, some liquid over the minimum calculated amount is needed to account for slight variations in manufacturing of the small tubes and in the filling procedures and variations in the application for different operating conditions. The surplus of fluid over the minimum amount will be taken by the rotating "g" forces to the tip of the boiler when the tube is in a rotating system as a turbine. This excess of liquid will remain there during operation in the rotating system. If too much liquid is carried in the tip of the boiler a large increase in temperature occurs due to the liquid head. The maximum fill level will be made up of the minimum weight of fluid required for proper system balanced operation as just described plus a weight of fluid which,

during operation, will fill the tube to the thickness of the thermal boundary layer of the hot gas flowing over the boiler tip. This thickness may be of the order of 10% of the boiler height for a typical application.

It should be noted that the tube need not be completely radial to the axis of rotation 24 as shown in FIGURE 2 although, in practice, it will generally be so oriented. However, operation may take place with the tube canted as in the turbine bucket up to a maximum limit of 70° from the radial to the axis of rotation of the bucket or the horizontal reference axis. In other words, the tube may, if constructed and filled as described above, be tipped to as low as 20° off the horizontal and still operate as desired.

In summary, the boiling and condensing heat transfer system described provides a system which sizes the tube correctly so that at no point is sonic velocity exceeded and it provides the maximum area of the tube generally at the interface between the vapor and liquid phases. In addition, the invention provides a minimum fill or supply of liquid so that the system operates balanced without an excess capacity to reduce the heat transfer capabilities. The system of the invention may be applied to straight or tapered tubes although the tapered tubes generally provide for better vapor flow for best heat transfer.

While there has been described a preferred form of the invention, obvious equivalent variations are possible especially in the structural form of tapering in light of the above teachings. It is therefore to be understood that within the scope of the appended claims, the invention may be practiced otherwise than as specifically described, and the claims are intended to cover such equivalent variations.

We claim:

1. A fluid boiling and condensing heat transfer system for use on a structure to be cooled comprising; a sealed tubular member within the structure, a fluid disposed in the tube, said tube being oriented to provide a boiler at one end for vaporizing said fluid and a condenser at the other end and being sized to have a minimum area and sonic velocity of the vaporized fluid at the interface between boiler and condenser portions in accordance with the heat to be transferred at a given temperature from the member to the liquid for condensing said liquid such that:

$$A_t = H/\rho CL$$

where:

A_t = tube cross-sectional area in ft.² of the tube at the interface between said boiler and condenser portions,

H = desired heat transferred from the boiler portion in B.t.u.'s/hr.,

ρ_{sat} = density of the vapor in pounds/ft.³ at saturation,

C = sonic velocity in feet/hour of the vapor at saturation,

L = latent heat of vaporization of the fluid at saturation in B.t.u.'s/pound,

and the minimum amount of said fluid in the tube is the sum of the fluid vapor weight (g) and the fluid liquid weight (g') where;

Fluid vapor weight in pounds (g) =

$$\int_{\text{condenser base}}^{\text{boiler tip}} \rho_v A_t dx$$

where:

ρ_v = vapor density in pounds/ft.³,

A_t = tube cross-sectional area in ft.²,

x = incremental length (dx) in feet,

integrated between the limits of the condenser base and the boiler tip and;

Fluid liquid weight in pounds (g') = $\int \rho_L P \delta dx$

where:

ρ_L =liquid density in pounds/ft.³,
 P =tube perimeter in feet,
 δ =film thickness in feet,
 x =incremental length in feet,

5

integrated between the same limits whereby the desired amount of liquid for boiling and condensing is supplied for maximum heat transfer at the given temperature. 10

2. Apparatus as described in claim 1 wherein said structure to be cooled is a rotating turbine bucket, having a bladed portion across which relatively hot gases pass, said tube is positioned so that said boiler portion extends into said bladed portion of said turbine bucket and, said condenser portion extends inwardly of said bladed portion for passage of cooling fluid thereacross. 15

3. A liquid metal boiling and condensing heat transfer system for use on a structure to be cooled comprising; a sealed tubular member within the structure, a liquid metal disposed in the tube, said tube being oriented to provide a boiler at one end for vaporizing the fluid and a condenser at the other end and being sized to have a minimum area and sonic velocity at the interface between said boiler and condenser portions and said tube being substantially tapered from said interface, the limits on said taper being that which produces at any point along the tube sonic velocity as a maximum, said minimum area sizing being in accordance with the heat to be transferred at a given temperature from the member to the liquid for boiling said liquid such that; 20

$A_t = H / \rho_{sat} CL$ in feet where:

35

A_t =cross-sectional area in ft.² of the tube at the interface between the boiler and condenser portions,

H =desired heat transferred from the boiler portion in B.t.u.'s/hr. 40

ρ_{sat} =density of the vapor in pounds/ft.³ at saturation,

C =sonic velocity in feet/hour of the vapor at saturation,

L =latent heat of vaporization of the fluid at saturation in B.t.u.'s/pound, 45

and the minimum amount of said liquid in the tube is the sum of the fluid vapor weight (g) and the fluid liquid weight (g') where;

Fluid vapor weight in pounds (g) =

$$\int_{\text{condenser base}}^{\text{boiler tip}} \rho_v A_t dx$$

ρ_v =vapor density in pounds/ft.³,

A_t =tube cross-sectional area in ft.²,

x =incremental length (dx) in feet,

integrated between the limits of the condenser base and the boiler tip and;

Fluid liquid weight in pounds (g') = $\int \rho_L P \delta dx$

where:

ρ_L =liquid density in pounds/ft.³,

P =tube perimeter in feet,

δ =film thickness in feet,

x =incremental length in feet,

integrated between the same limits whereby the desired amount of liquid for boiling and condensing is supplied for maximum heat transfer at the given temperature.

4. Apparatus as described in claim 3 wherein said structure to be cooled is a rotating turbine bucket having a bladed portion across which relatively hot gases pass, said tube is positioned so that said boiler portion extends into said bladed portion of said turbine bucket and, said condenser portion extends inwardly of said bladed portion for passage of cooling fluid thereacross.
